UNITED STATES PATENT OFFICE.

DON L. QUINN, OF OAK PARK, ILLINOIS, ASSIGNOR TO CHICAGO MILL AND LUMBER COMPANY, A CORPORATION OF ILLINOIS.

POULTRY-FEEDING COOP.

1,255,834.

Specification of Letters Patent. Patented Feb. 5, 1918.

Application filed October 21, 1916. Serial No. 126,912.

To all whom it may concern:

Be it known that I, DON L. QUINN, a citizen of the United States of America, and a resident of Oak Park, county of Cook, and State of Illinois, have invented certain new and useful Improvements in Poultry-Feeding Coops, of which the following is a specification.

This invention relates to poultry coops and more particularly to those adapted for confining the poultry while fattening, and also while awaiting sale.

Heretofore, the crates used for confining poultry while fattening and when held in the market pending disposal have been of a substantially unitary character respecting the frame and floor construction. Such crates cannot be cleaned or kept sanitary without handling the whole crate, and a battery or stack of such crates cannot be cleaned without taking the battery apart. Hence it occurs that crates are frequently permitted to become unsanitary and objectionable, particularly in market places.

The main objects of the invention are to provide an improved form of poultry crate of more sanitary character than the crates commonly used heretofore; to provide a removable roost or floor member of grid-like character adapted for ready withdrawal so as to facilitate frequent cleaning and thereby to promote coop sanitation; to provide such a crate of simple and inexpensive but durable construction; and to provide crates of the foregoing character adapted for grouping or stacking in a battery.

An illustrative embodiment of the invention is shown in the accompanying drawings, in which—

Figure 1 is a perspective view of a complete crate with part of the front broken away so as to disclose certain details of construction.

Fig. 2 is a perspective view of an end or fragment of one of the slidably removable floor members, apart from the crate.

In the embodiment shown in the drawings, the coop 1 comprises two compartments 2 and 3 respectively separated by the partition 4. The coop comprises a plurality of frame bars 5 and 6 disposed vertically and horizontally, respectively, as well as the bearing rails 7, and the intermediate slat members 8 constituting the walls and top. Each compartment 2 and 3 is provided with a remov-

able roost or floor 9 of grid-like character comprising a pair of bars or rails 10 spaced apart and connected by a series of cross members or slats 11, the ends 12 of which are arranged to project somewhat beyond 60 said rails 10, in order to bear upon the lower frame bars 5.

The coop is also provided with a sliding slat or door 13, removably mounted in the top and common to both compartments. 65 Moreover, two adjacent front slats 8 of each compartment are removable to provide lateral access, as understood in the art. Provision is made for placing a moisture-tight pan 14 in the lower part of the crate beneath 70 the removable roost. Said pan rests on the bearing rails 7 and is also removable by sliding forward, in substantially the same manner as the roost members 9.

The drip pans and roost grids are mounted 75 in the crate merely by sliding the same into place where ordinarily they will be held by friction and gravity, and may be further secured if desired by any suitable means, though positive fastenings are not 80 usually necessary or desirable. Whenever it is desired to clean the crate, it is only necessary to withdraw the pans and roost grids respectively and wash the same in any manner that may be found convenient, and they 85 may be sterilized if desired, as for instance by a steam jet.

The crate compartments are preferably of a small size adapted to accommodate not more than four birds each, in order to promote fattening and to prevent too much activity.

The crates are made in various sizes, ranging in capacity from one to eight compartments, and crates of a given size are formed 95 and adapted for assembling or stacking in "batteries" of any desired height, in order to economize in space. When so grouped, the crates are capable of being kept sanitary by removing and cleaning the roosts and 100 pans frequently, and without taking the battery apart. When the crates are separate from one another, the top slat 13 is preferably used as a door, but when assembled in a battery, the side doors or slats may 105 be opened.

Although but one specific embodiment of this invention has been herein shown and described, it will be understood that numerous details of the construction shown may be al- 110

tered or omitted without departing from the spirit of this invention as defined by the following claim.

I claim:—

- 5 In a poultry coop, a frame including a pair of rails disposed in spaced parallel relation at or adjacent to the bottom, a plurality of cross-pieces secured to the underside of said rails, a removable drip-pan
10 slidably mounted on said cross-pieces for insertion and removal crosswise thereof between said rails, and a removable roost com-

prising a pair of bars spaced apart with a series of slats secured crosswise thereon with their ends projecting sufficiently to rest on ¹⁵ said rails for supporting said roost, said drip-pan and roost being suitably spaced apart by said rails and being removable by sliding forward, each independently of the other.

Signed at Chicago this 16th day of Oct. ²⁰
1916.

DON L. QUINN.
